UNITED STATES PATENT OFFICE.

GEORGE F. HANDLEY, OF GLENDALE, NEW YORK, ASSIGNOR TO ROYAL TYPEWRITER COMPANY, INC., OF NEW YORK, N. Y., A CORPORATION OF NEW YORK.

TYPEWRITING MACHINE.

Application filed November 24, 1926. Serial No. 150,448.

In certain classes of card work it is necessary to write upon the extreme top edge of the card and since in such cases the cards are frequently of a form which permits of interlocking for unit filing and accordingly have projecting locking points of peculiar shape, there is danger that the card will become entangled with the card guide, the ribbon vibrator, or the platen scale mechanism usually found in typewriting machines.

It is, therefore, the purpose of this invention to provide a card holding strip which shall be carried by the platen and which shall overlie the lower edge of the card so that the writing on the card may be performed without any danger of interference from any part of the mechanism.

This card holding strip is of metal and curved in accordance with the contour of the platen and is detachably held at its ends for ready removal. On the inner side of the strip are provided a plurality of springs in the form of flat metal members fastened to the card holding plate at one end and having the other end free. The free ends of these springs tend to force the card holding plate away from the platen. Two or more of the springs are preferably located to extend longitudinally of the platen while the other is placed near one edge and extends circumferentially of the platen. The two longitudinal springs are preferably placed nearer one edge of the strip than the other and the result of their action together with that of the circumferentially extending spring is to cause one edge of the holding plate to be spaced from the platen sufficiently to permit the ready insertion of the lower edge of the card. When inserted, the longitudinally extending springs form stops for the inserted edge while the circumferentially extending spring which is preferably located at the left hand side forms a stop for positioning the left hand edge of the card so that one card after another can be inserted for writing and the writing will always occupy the same relative position on the cards.

There is also provided a lever or handle attached to the platen axle and provided with two spaced arms which coact with an adjustable stop on the carriage frame to limit the turning movement of the platen in either direction. The parts are so adjusted that when one limit of movement is reached, the card will be in position for writing upon the

extreme top edge thereof, and when the other limit is reached for the purpose of removing the card and inserting a new one, the lower edge of the card holding strip will not pass above the edge of the card scales usually carried by the carriage.

Further features of the invention will be apparent from the following detailed description and set forth in the appended claims.

In the drawings:

Figure 1 is a front elevation with portions of the carriage of a typewriting machine showing the platen equipped with the present invention.

Figure 2 is a perspective view of the card holding plate removed from the platen.

Figure 3 is a view of the left hand end of the platen equipped with the holding plate.

Figure 4 is a longitudinal section of the right hand end of the platen with the card holding plate in position.

Figure 5 is a view of the right hand side of the platen and a portion of the carriage showing the platen turned to one limit of its movement.

Figure 6 is a similar view showing the platen turned to the opposite limit of movement.

There is illustrated in the drawings a portion of the carriage A having mounted therein in the usual manner a platen B having an axle b and against which bear the usual rear and front feed rolls C and D. A type guide E is provided through which type bars F pass to the printing point and a card holding scale G, card holding fingers H and end scales I are all supported from the shifting carriage frame as usual in the Royal machine. These parts, however, may be varied widely in construction without affecting the scope of the invention so that the illustration is not to be regarded as limiting the invention.

Attached to the left hand end of the platen is a small plate 1 which may be fastened by screws 2 or in any suitable manner and is provided with an opening 3. At the right hand end of the platen a plate 4 fits loosely over the bushing surrounding the platen axis and is held in position by two screws 5 at diametrically opposite sides which, however, do not hold the plate firmly against the end of the platen but allow it to oscillate

slightly. At one side a spring 6 is contained in a hole 7 in the head of the platen and bears against the plate 4, thus forcing it outwardly at this edge. The opposite edge has 5 a cutout or hole 8 similar to the hole 3 in the plate 1 and also has a finger piece 9 bent outwardly therefrom.

The card holding plate 10 of thin sheet metal has an ear 11 at each end near the 10 lower edge and this ear is shaped so that it will fit into the opening 8 or the opening 3 respectively. When the plate is in position and it is desired to remove the same, the pressure of the finger piece 9 will rock the plate 4 against the tension of the spring 6 and disengage this plate from the lug or projection 11 on the card holding member 10. The card holding plate can then be 15 lifted and turns about the engagement of the lug 11 with the opening 3 in the plate 1 as about a pivot until it reaches a position such that it may be readily disengaged from said opening. When it is again desired to 20 replace the plate, the opposite sequence of actions is followed.

On the inside of the card holding plate are provided two flat spring members 12 which are soldered, riveted or otherwise fastened at one end to the plate and the opposite end of each member tends to swing outwardly as indicated in Figure 2. A similar spring member 13 is placed near the left hand edge and extends circumferentially of the platen. Its free end also tends to spring outwardly. Since the engagement of the lugs 11 with the plates 1 and 4 in effect provides a pivotal mounting for said plate at one edge thereof, it is obvious that the front edge of the plate will be forced outwardly 35 from the platen to an extent sufficient to permit the ready insertion of the card from this edge. The lower edge of the plate, however, will engage firmly with the platen and prevent any interference between this edge 40 of the plate and any of the other accessories of the platen or carriage. The springs 12 and 13 also act as positioning members for the card when inserted, since the springs 12 determine the position of the lower edge of 45 the card and provide means whereby it will be positioned in the proper relation to the printing line while the spring 13 provides a left hand edge guide for the card. If desired, the card holding plate 10 may be provided on its outer edge with an indicating line 14 denoting the position of the inner edge of the spring 13 so that the user may readily place the card in the desired position.

60 The handle 15 is attached by a set screw 16 to the platen axle b and the hub of this handle is provided with two arms 17 and 18. These arms coact with a screw 19 which has an eccentric head for the purpose of determining the extent of rotation of the

platen when being used for the purpose of writing cards. The eccentric screw 19 will be so adjusted that when the parts are in the Figure 5 position, the extreme upper edge of the card will be in position to be 70 written upon as shown by the type bar F in this figure. When the arm 18 contacts with the screw 19, the platen will have been moved to a position in which the card can be readily removed and another card 75 inserted. It will be noted that at this time the lower edge of the card holding plate has not moved upwardly far enough to interfere with the ribbon vibrator, card holding scales or other attachments of the platen. 80

It will be apparent that the handle 15 may be readily removed when it is not desired to use the same and that the card holding plate 10 may also be removed very quickly and easily. A machine can, therefore, be 85 equipped for use with this plate for the purpose of writing cards without destroying its efficiency for use as a usual typewriting machine whenever it is desired to use the same for this purpose. Obviously various detail changes may be made in the precise construction of the invention without departing from the spirit thereof, so that the invention is to be regarded as limited only by the scope of the appended claims. 95

I claim as my invention:

1. A card holding attachment for a platen comprising a plate curved similarly to the curvature of the platen, means at each end of the plate for attaching the same to the platen, and a plurality of flat springs attached to the inside of the plate and engaging the platen. 100

2. A card holding attachment for a platen comprising a plate curved similarly to the curvature of the platen, means at each end of the plate and adjacent one edge for attaching the same to the platen, and a plurality of flat springs attached to the inside of the plate and engaging the platen, said springs moving one edge of the plate away from the platen. 105

3. A card holding attachment for a platen comprising a plate curved similarly to the curvature of the platen, means at each end of the plate for attaching the same to the platen, and a plurality of flat springs attached to the inside of the plate and engaging the platen, said springs providing side and edge gages for the inserted card. 115

4. A card holding attachment for a platen comprising a plate curved similarly to the curvature of the platen, means at each end of the plate and adjacent one edge for attaching the same to the platen, and a plurality of flat springs attached to the inside of the plate and engaging the platen, said springs moving one edge of the plate away from the platen, and said springs providing side and edge gages for the inserted card. 125

5. A card holding attachment for a platen comprising a plate curved similarly to the curvature of the platen, a lug at each end of the plate and adjacent one edge, means at each end of the platen receiving said lugs, one of said means being movable to release its cooperating lug, and spring means between the inside of the plate and the platen. 30
- 10 6. A card holding attachment for a platen comprising a plate curved similarly to the curvature of the platen, a lug at each end of the plate and adjacent one edge, means at each end of the platen receiving said lugs, one of said means being movable to release its cooperating lug, and spring means between the inside of the plate and the platen, said spring means also serving as positioning guides for the inserted card. 35
- 15 7. A card holding attachment for a platen comprising a plate curved similarly to the curvature of the platen, a lug at each end of the plate and adjacent one edge, a fixed member at one end of the platen having means to engage one lug, a movable member at the other end of the platen to engage the other lug, spring means to hold this member and lug in engagement but permitting relative movement for removing the 40
- 20 25 45
8. A card holding attachment for a platen comprising a plate curved similarly to the curvature of the platen, a lug at each end of the plate and adjacent one edge, a fixed member at one end of the platen having means to engage one lug, a movable member at the other end of the platen to engage the other lug, spring means to hold this member and lug in engagement but permitting relative movement for removing the 40
- 30 35 40
9. A card holding attachment for a platen comprising a plate curved similarly to the curvature of the platen, means at each end of the plate for attaching the same to the platen, spring means between the plate and platen for normally urging one edge of the plate away from the platen, means for turning the platen, and an adjustable stop to limit the turning movement in one direction 50
- 45 50 55

In testimony whereof, I have hereunto subscribed my name.

GEORGE F. HANDLEY.
